ATTY.

UNITED STATES PATENT OFFICE.

ARION S. KALENBORN, OF SAN FRANCISCO, CALIFORNIA.

X-RAY APPARATUS.

Application filed March 9, 1921, Serial No. 450,903. Renewed May 11, 1925.

To all whom it may concern:

Be it known that I, ARION S. KALENBORN, a citizen of the United States, residing at San Francisco, in the county of San Francisco and State of California, have invented new and useful Improvements in X-Ray Apparatus, of which the following is a specification.

This invention relates to an X-ray apparatus, and particularly pertains to an apparatus embodying the use of extra high potential X-ray tubes.

The prime object of the present invention is to provide means whereby extra high potential electric currents may be produced and utilized in connection with X-ray tubes to produce control and give direction to higher series X-rays of shorter wave length and higher frequency, and other rays, such as those of the gamma series, without current losses or dangers which might arise due to leakage and sparking.

The present invention contemplates the use of a transformer and rectifier for producing unidirectional high potential electric currents which are delivered to an X-ray tube, said apparatus being used in connection with a filament transformer when required, all of which apparatus is electrically connected and is enclosed within an oil filled tank, being thereby oil cooled and insulated.

The invention is illustrated by way of example in the accompanying drawing, in which:

Fig. 1 is a view in perspective showing the present invention.

Fig. 2 is an enlarged fragmentary view of the tube adjustment.

Fig. 3 is a view in diagram showing the arrangement of parts of the apparatus.

Referring more particularly to the drawings, 10 indicates a tank preferably formed of metal. This tank is lead lined and has a window 11 in the walls thereof formed of material transparent to X-rays. This window is so formed as to permit the patient to be disposed in front or above the tank. Disposed in the rear of this window is an X-ray tube 12. When this tube is of the "Coolidge" filament type a filament transformer 13 is connected therewith, and this transformer is enclosed within the tank. The tank contains a transformer 14 which is designed to step up the potential of a current from any initial low voltage to a de-

sired higher voltage, as for example, from 220 volts to 200,000 volts.

The transformer is constructed with sectional windings of the general arrangement disclosed in the Patent No. 1,195,733, granted to Frank Rieber, August 22, 1916. The secondary windings of this transformer are electrically connected with contact members of a mechanical rectifier 15. The rectifier is preferably of the type disclosed in my co-pending application, filed December 15, 1920, and bearing the Serial No. 431,021. All of this apparatus is submerged in oil within the tank and is there equipped with the necessary electrical connections and means for properly controlling and directing the various functions of the elements such as the adjustment device 16 for changing the direction of the X-ray travel. The adjusting device is shown consisting of an operating shaft extending exteriorly of the tank and provided at its inner end with a worm which meshes with a gear carried by the X-ray tube. By rotating the shaft the gear and X-ray tube are partially rotated to direct the rays through a selected portion of the window which is substantially concentric with the X-ray tube. The shaft is provided near its outer end with a finger which is movable over graduations for indicating the position of the X-ray tube with relation to the window.

In operation of the apparatus, low voltage current is delivered to the primary windings of the transformer 14. The secondary currents produced in the sectionalized secondary windings of the transformer are delivered to the rectifier, where high potential alternating current will be converted to form unidirectional electric currents, which are then delivered to the X-ray tube. In the event that a filament transformer is required, this is electrically connected to perform its necessary function in connection with the tube.

The difficulty experienced in handling high voltage in connection with X-ray work is well known, and by forming the oil filled tank 10 of metal lead lined and well grounded, the danger incident to the production of X-rays and high potential currents will be substantially eliminated. This danger will be further decreased due to the fact that the X-ray apparatus will be submerged in oil, and the rays of the gamma series will be emitted through the window 11.

It will thus be seen that the apparatus here disclosed provides simple and effective means for practically handling high voltage currents in connection with X-ray tubes.

5 While I have shown the preferred form of apparatus, as now known to me, it will be understood that various changes might be made in the combination, construction, and arrangement of parts, by those skilled in 10 the art, without departing from the spirit of the invention as claimed.

Having thus described my invention, what I claim and desire to secure by Letters Patent is:

- 15 1. An electrical apparatus comprising a closed container having a window, a dielectric medium filling said container, an X-ray tube entirely submerged within said medium, a transformer, and a rectifier also submerged within said medium, said transformer and rectifier being connected with the X-ray tube and operating means remote from the X-ray tube for rotating the same with respect to the said window.
- 25 2. An electrical apparatus comprising a closed container having a dielectric medium, and provided with a window, an X-ray tube entirely submerged within the said medium, a transformer and rectifier also submerged 30 within the said medium and connected with the X-ray tube, operating means remote from the X-ray tube for rotating the same with respect to the window and indicating means associated with the operating means,

said operating means and indicating means 35 being arranged exteriorly of the casing.

3. An electrical apparatus comprising a closed container having a window and provided with a dielectric medium, a rotary X-ray tube entirely submerged within the 40 said medium and adapted to be adjusted with relation to the said window, a transformer and a rectifier both submerged within the said medium and connected with the X-ray tube, gearing connected with the X-ray tube for rotating the same and having an exteriorly arranged operating element remote from the X-ray tube and indicating means exteriorly arranged and associated 45 with the operating element.

50 4. An electrical apparatus comprising a closed container having a window and provided with a dielectric medium, a rotary X-ray tube entirely submerged within the said medium and adapted to be adjusted 55 with relation to the said window, a transformer and a rectifier both submerged within the said medium and connected with the X-ray tube, a pinion connected with the X-ray tube, an operating shaft extending to 60 a point exteriorly of the container and remote from the X-ray tube and having a worm meshing with the said pinion, an indicating pointer mounted on the shaft exteriorly of the casing, and graduations 65 associated with the indicating pointer.

ARION S. KALENBORN.
